(57) **CLAIM**

The ornamental design for a dispenser for liquid soap, as shown and described.

DESCRIPTION

FIG. 1 is a perspective view of a dispenser for liquid soap showing our new design;

FIG. 2 is a front elevation view thereof;

FIG. 3 is a side elevation view thereof;

FIG. 4 is a rear elevation view thereof; and,

FIG. 5 is a top view thereof.

The subject matter shown in broken lines is for illustrative purposes only and forms no part of the claimed design. The bottom view (not shown) forms no part of the claimed design.
